UNITED STATES PATENT OFFICE

2,223,380

MACHINE GUN

Charles J. Michal, Jr., Hinsdale, Ill.

Original application September 23, 1936, Serial No. 102,100. Divided and this application October 7, 1937, Serial No. 167,814

2 Claims. (Cl. 42—49)

My invention relates to machine-guns and to devices for converting other firearms into machine-guns.

More specifically my invention relates to an improved many-round magazine for use with the fully automatic pistol of my U. S. Patent No. 2,056,975, issued October 13, 1936, or with the convertible fully automatic semi-automatic pistol of my copending application for U. S. patent, Serial No. 102,100, filed September 23, 1936, of which this present application is a division.

Without such a magazine the fully automatic features of the two above mentioned types of firearm cannot be utilized to the utmost.

In addition to the foregoing object, I have worked out a number of novel and useful details, which will be readily evident as the description progresses.

My invention consists in the novel parts, and in the combinations and arrangements thereof—and especially in the converter, the magazine and the stock thereof—which are defined in the appended claims; and of which one embodiment is exemplified in the accompanying drawings, which are hereinafter particularly described and explained.

Throughout the description, the same reference number is applied to the same member or to similar members.

Figure 1 is a side elevation of my complete firearm, showing my magazine in place.

Figure 2 is an enlarged side elevation of the magazine of my weapon, the viewpoint being at a slant slightly to the rear of the viewpoint of Figure 1.

Figure 3 is the follower-spring of my magazine, disassembled.

Figure 4 is a rear elevation of the cover of my magazine, taken along the line 4—4 of Figure 2.

Figure 5 is the view from the inside of the cover shown in Figure 4.

Figure 6 is a side view of this cover, taken along the line 6—6 of Figure 5, it is partly cut away to show the spiral spring inside.

Referring to the drawings, and more particularly to Figure 1, it will be seen that this figure illustrates the conventional Colt automatic pistol of the United States Army, as modified in my copending application, to render it convertibly fully automatic or semi-automatic at will.

Referring to Figure 1, we see that 11 is the well-known conventional Colt semi-automatic pistol of the United States Army. 12 is a combined forward handle and blast deflector. 13 is

an auxiliary stock. 14 is the converter, whereby my weapon is rendered fully automatic or semi-automatic at will. And 15 is my improved magazine.

Feature 15 is the subject-matter of this present application. Features 12, 13 and 14, and various combinations of all or some of the four features are the subject-matter of my copending application.

Turning now to Figures 2 to 6, for the details of my magazine, we see that part 16 is identical to the conventional Colt magazine, but with the bottom removed. Parts 17 and 18 constitute the conventional Luger magazine, consisting of a truncated conical portion 17, and a tangential portion 18. I connect these two magazines together by the intermediate portion 19. The angle (substantially 20°) at which I set the Colt magazine to the Luger magazine constitutes an important feature of my invention; as will now be explained.

It is at this point in my invention that I depart from the conventional Luger construction. In the Luger, the part which corresponds to my part 16 is materially narrower than the length 25 of the cartridges, which accordingly lie in echelon, nose up. Luger's follower is coplanar with the axis of his cone, and his portions 18 and 17 join his portion 16 at such an angle that the cartridges are presented to portion 16 at the 30 slant above referred to.

This construction requires, when filling his magazine, the insertion of the cartridges one by one, by means of a loading-tool, which is apt to get lost, and without which the owner of a 35 Luger is helpless.

In a Colt, on the contrary, the cartridges lie with their bases very nearly parallel to the edge 44 of the portion 16, and hence may be loaded by hand through end 40, which process is much 40 more speedy, and has no tool to lose.

Of course, I could have modified my portion 16 by inserting a false back along edge 44, and then have employed the Luger portions 17 and 18 unmodified. But this would have necessitated 45 using the loading tool, which I was seeking to eliminate.

I determined the angle of attachment between my portions 18 and 16 as follows. Making a diagram of portions 16 and 19, I laid a cartridge 50 in the proper position at end 40 of the diagram, and then laid other cartridges side by side upon the diagram until they reached the further end of portion 19. The angle between the base of the last cartridge, and the edge 44 of portion 16, 55

was the angle employed by me for attaching portion 18. The reason why I could not simply employ the inclination of the base of the first cartridge, is due to a slight difference in width at 5 point and base of the particular ammunition.

Furthermore, I found that, if a less angle were employed, the bullets would nose-down, upon emerging from end 40, and, instead of entering the chamber of the gun, would jam. Whereas, 10 if a greater angle were employed, the magazine would not load by hand. These considerations determine the exact angle for use with any particular caliber of gun and type of ammunition. In the exemplification shown, it happens to 15 be 22.5°.

The cover 20 of the Luger magazine has a truncated conical portion 21 which projects into the truncated conical portion 17 of the magazine, leaving between them a space 22 just wide 20 enough to hold a row of cartridges. I have had to modify the depth of this cover, to fit American ammunition, but it remains functionally the same. Portion 21 contains a very powerful spiral spring 23. This spring is attached to shaft 24, 25 and is initially set so as to hold the follower 25 firmly against notch 26 in guide 27. Keyed to the opposite end of shaft 24, on the outside of cover 20, is lever 28. Pivoted on the outer end of lever 28 is a handle 29.

30 The spring 30, shown in Figure 3, is inserted with its wide end 31 in the Colt magazine 16, and its small end bearing against the face 33 of follower 25. This face is bent back by me at an angle from the conventional Luger position.

35 Without such bending, I found that even my careful calculation of the other angle, already discussed, would avail me nothing—the bullets would jam. The angle at which to set the follower should be substantial; practically equivalent to the other angle already discussed, or even 40 slightly more. All this is empirical.

About twelve cartridges can be inserted in the Colt magazine in the ordinary way, until spring 30 is compressed to the utmost. To insert more 45 cartridges, handle 29 is swung down to its extended position, shown in dotted lines at the bottom of Figure 4. It, and lever 28, are then rotated clockwise to the dotted position shown at the right in Figure 4. Plunger 34 (see Figures 2 50 and 6) is then depressed against its spring 35, until its foot 36, enters the wide portion 37 of the slot 38. Upon releasing the manual pressure on handle 29, foot 36 catches in the narrow portion 39 of the slot.

55 Follower 25 is now in its fully retracted position, as shown dotted in Figure 5, and the rest of the cartridges can now be inserted by hand, at the end 40 of the magazine, against merely the light pressure of spring 30.

When the magazine has thus been charged, foot 36 is released from slot 38, and handle 29 is folded back into its normal position. The magazine is now ready for use.

It is to be understood that the cover 20 is not 5 removed during this process, nor in fact ever except for repairs, it being secured in place by a single bolt through hole 41, and by screw 42 inserted in threaded hole 43.

It is to be understood that the word "follower" 10 in the claims refers to the follower 25, and not to the end 31 of the spring 30.

Having now described and illustrated one form of my invention, I wish it to be understood that my invention is not to be limited to the specific 15 form or arrangement of parts hereinbefore described, except insofar as such limitations are specified in the appended claims.

I claim:

1. In a magazine for an automatic or semi-automatic pistol, the combination of: a straight portion, of a width just sufficient to permit easy passage of the cartridges to be fired, and of a depth substantially that of the length of the cartridges; and a trunco-conical portion, set at 25 such an angle to the straight portion that, when the straight portion is filled with cartridges, the base of the last cartridge will be substantially parallel to the bases of the truncated cone; a long spiral spring within the two portions, and 30 having at one end cartridge-impelling means; and a spring-actuated follower within the trunco-conical portion, pivoted at the axis of the trunco-conical portion, and bearing on the other end of the long spring, the relative inclination 35 between the bearing face of the follower and that end of the spring against which it bears being such as to bias the spring through a substantial angle, practically equivalent to the angle first referred to.

2. In a magazine for an automatic or semi-automatic pistol, the combination of: a straight portion, of a width just sufficient to permit easy passage of the cartridges to be fired, and of a depth substantially that of the length of the cartridges; and a trunco-conical portion, set at 45 an angle to the straight portion; a long spiral spring within the two portions, and having at one end cartridge-impelling means; and a spring-actuated follower within the trunco-conical portion, and bearing on the other end of the long spring, the relative inclination between the bearing face of the follower and the cartridge-impelling means being such as to bias the latter to assume a substantial angle with respect to the 50 depth of the straight portion of the magazine, practically equivalent to the angle first referred to.

CHARLES J. MICHAL, JR.
